UNITED STATES PATENT OFFICE.

WILLIAM HASLAM, OF PHILADELPHIA, PENNSYLVANIA, ASSIGNOR TO
DAVID S. CRESWELL, OF SAME PLACE.

FURNACE-GRAVE.

SPECIFICATION forming part of Letters Patent No. 352,318, dated November 9, 1886.

Application filed April 27, 1885. Serial No. 163,519. (No model.)

To all whom it may concern:

Be it known that I, WILLIAM HASLAM, a citizen of the United States, and a resident of Philadelphia, Pennsylvania, have invented 5 certain Improvements in Furnace-Grates, of which the following is a specification.

My invention consists of improvements in the construction of shaking and dumping grates, more especially adapted to furnaces and heat-roers; and the main object of my invention is to construct a grate that can be applied in place of a worn-out grate of the ordinary construction without disturbing the furnace and linings.

15 In the accompanying drawings, Figure 1 is a sectional elevation of part of a hot-air furnace with my improved grate in position; Fig. 2, a detached perspective view of the grate; Fig. 3, a detached perspective view of 20 the grate-frame, and Figs. 4 and 5 perspective views of the hangers for the frame.

A is the ash-pit of the furnace, and B the combustion-chamber, lined, as usual, with fire-brick, which rest on a circular plate, a, the 25 ash-pit being provided with the usual door, b.

D is the grate, made in a circular form and having a series of concentric bars, m, connected together by webs n, as shown in Fig. 2.

A pivot-pin, d, projects from the center of the 30 grate and fits into a socket, d', on a frame, E, which is of rectangular shape, as shown in Fig. 3. This frame is provided with pivot-pins i i, one on each side of the frame, which are adapted to bearings i' on upright posts I, 35 Figs. 1 and 4. On the under side of a projection, h, on the front portion of the frame E are formed bearings for a shaft, F, which is 40 squared at its outer end, g, and is provided with a pinion, f, at its inner end, which gears with a circular rack, e, on the under side of the grate E. The pivot-pins i i are arranged 45 on the frame E forward of the center of the grate, as shown by the dotted line, Fig. 3, and also in Fig. 1. The weight of fuel on the rear of the frame thus prevents the tilting of the frame of the grate, which can, however, be easily dumped by withdrawing the bolt k, attached to the plate a, in any suitable manner, and entering a recess, l, in the frame, and the

grate can be easily returned to its normal position by either a small chain, w, attached to the front of the frame and passing through an eye, y, on the plate a, or by the use of a poker, and the retaining-bolt k can then be reinserted in the recess l.

The grate E is rotated or reciprocated by a handle, (shown by dotted lines in Fig. 1,) which fits over the squared end of the shaft F. By turning this handle the grate is rotated through the medium of the pinion f and circular rack e.

On the grate are a number of small projections, j, for breaking up the clinker as the grate is turned.

The grate-frame E may, when circumstances 65 permit, be hung from small hangers I', Fig. 5, secured to the under side of the plate a; but I prefer to use the standard I, which can be placed on the ash-pit floor and can be easily made to fit any height of ash-pit.

I claim as my invention—

1. The combination of a rotary grate, D, with a swinging grate frame, E, the grate pivoted to the frame to turn thereon in a horizontal plane, and the frame pivoted at i in 75 front of the pivot of the grate, as set forth.

2. The combination of the frame E, of rectangular form, pivoted at its sides in the furnace-casing, and having a socket, d', with a grate having a central pivot-pin, d, adapted 80 to the socket, a shaft, F, in bearings in the front portion of the frame, and having a pinion, f, gearing with a circular rack on the under side of the grate, substantially as set forth.

3. The combination of the pivoted frame E, a grate, D, pivoted to rotate thereon, and the frame E, pivoted off the center of the grate D, with a chain, w, connected to the frame for returning the grate to its normal position 90 after dumping, substantially as specified.

In testimony whereof I have signed my name to this specification in the presence of two subscribing witnesses.

WILLIAM HASLAM.
